CABINET FOR A CAN OPENER

Barry L. Smith, Overland, and William E. Gundelfinger,
House Springs, Mo., assignors to The Dazey Corporation,
St. Louis, Mo., a corporation of Missouri

Application January 9, 1958, Serial No. 49,176

Term of patent 14 years

(Cl. D22—2)

FIG. 1.

FIG. 2.

FIG. 3.

FIG. 4.

FIG. 5.

Fig. 1 is a top plan view of a cabinet for a can opener showing our new design;

Fig. 2 is a perspective view showing the front, top and right hand side of the said cabinet;

Fig. 3 is a perspective view showing the front, top and left hand side of the said cabinet;

Fig. 4 is a perspective view of the said cabinet as it appears with the can compartment in open position; and

Fig. 5 is a perspective view of the said cabinet as it appears with the side compartment thereof in open position.

The back of the said cabinet is plain.

We claim:

The ornamental design for a cabinet for a can opener, substantially as shown and described.
